UNITED STATES PATENT OFFICE.

CLARENCE H. WILLIAMSON, OF ALTOONA, PENNSYLVANIA.

TRUCK SIDE FRAME.

Application filed May 1, 1920. Serial No. 378,169.

To all whom it may concern:

Be it known that I, CLARENCE H. WILLIAMSON, a citizen of the United States, residing at Altoona, in the county of Blair 5 and State of Pennsylvania, have invented certain new and useful Improvements in Truck Side Frames; and I do hereby declare the following to be a full, clear, and exact description of the invention, such as 10 will enable others skilled in the art to which it appertains to make and use the same.

The invention relates to trucks for railway vehicles and more particularly to new and useful improvements in the construction 15 of side frames therefor.

The principal object of my invention, broadly stated, is to strengthen and simplify the construction of truck side frames. To this end the primary feature of the invention 20 consists in providing a side frame in which the compression member and the bolster guide columns are integral, and in providing a tension member having a recess or channel, portions of the compression 25 member being adapted to fit within the said recess.

Another feature of the invention consists in forming a truck side frame from two main members, the said members being provided 30 with interfitting portions and maintained in assembled relation by the journal box bolts.

Another feature of my invention consists in providing a compression member having 35 bolster guide columns integral therewith and a channel shaped tension member, portions of the compression member being adapted to have a wedging engagement with the flanges of the said tension member.

Another feature of my invention consists in providing a tension member having a 40 recess into which portions of the bolster guide columns extend, the said columns having projections adapted to underlie the spring plank whereby the spring plank 45 serves to maintain the columns in assembled position.

Still another feature of the invention consists in providing in combination with a 50 compression member a tension member having portions adapted to serve as journal box seats.

There are other features of the invention as will hereinafter more fully appear from 55 the detailed description of the particular

embodiments of the same which have been illustrated in the accompanying drawings, wherein:—

Figure 1 is a view in side elevation of a symmetrical portion of a truck side frame 60 constructed in accordance with my invention.

Fig. 2 is an end view of the construction shown in Fig. 1.

Fig. 3 is a sectional view on line 3—3 65 of Fig. 1, the section being viewed in the direction indicated by the arrows adjacent the ends of the said line.

Fig. 4 is a top plan view of the lower arch bar or tension member. 70

Fig. 5 is a view similar to Fig. 1 showing, however, a slight modification.

Fig. 6 is an end view of the construction shown in Fig. 5.

Fig. 7 is a sectional view on line 6—6 75 of Fig. 5, the section being viewed in the direction indicated by the arrows adjacent the ends of the said line.

Throughout the specification and drawings like parts are designated by like reference characters. 80

In the preferred form of my invention which has been illustrated in Figs. 1 to 4, inclusive, the side frame is generally designated by the numeral 1. It will be understood that while only a half portion of the side frame is illustrated the frame 1 is 85 symmetrical about its central vertical axis.

The top arch or compression member 2 preferably comprises a top web 3 and a 90 pair of downwardly directed flanges 4, 4, the said flanges adjacent the central portion of the side frame being shaped to form a bolster opening 5 and being cut away intermediate the bolster opening in 95 the end portions of the frame as at 6 to lighten the side frame. The portions of the flanges 4 intermediate the openings 5 and 6 form the bolster guide columns 7. The said columns are connected, adjacent the 100 opening 5, by the web 8. The lower ends of the said columns are preferably extended laterally towards the center of the said frame as shown at 9, and may be provided with a shoulder 10 intermediate the ends 105 of the said extensions. The side walls 11 of the laterally extending portions 9 are inclined inwardly as at 12, the object and purpose of which will be hereinafter described. The web 8 extends below the bot- 110

tom wall of the bolster opening and preferably follows the side edges of the extension 9 and forms the bottom wall of the inclined portion 12.

5 Adjacent the ends of the member 2 the top web 3 is inclined downwardly as at 13, and the lower edges of the webs or flanges 4, which at this point are preferably inwardly inclined as clearly shown at 14 in 10 Fig. 2, are connected by a transversely extending web or wall 15. In brief, the end portions of the compression member are preferably arranged to form a hollow box the side walls of which are inclined so 15 that box in section forms a blunt faced wedge. The bottom wall 15 is provided with a pair of spaced openings 16 each adapted to receive one of the journal box bolts. If desired these openings may be 20 reinforced by bosses 17 on the upper face thereof. Adjacent their inner ends the walls 15 may be provided with a curved portion 18 adapted to cooperate with the similarly formed portions of the lower arch bar 25 or compression member which will later be described.

Adjacent the upper end of each column 7 is provided a brake hanger bracket 19 which may conveniently be formed integral with 30 the web 4.

The upper web 3 of the member 2 is also provided with an opening 20, near each end of the said member, through which the inner journal box bolts may conveniently be inserted. It should be observed that the web 3 terminates a short distance beyond the bolt 35 openings 20 so that the said web is clear of the outer journal box bolts.

The lower arch or compression member 22 40 may conveniently be formed from a rolled or pressed beam and comprises a web 23 and flanges 24, the latter being preferably provided with outwardly extending lips or flanges 25. Said member 22 extends under 45 the bolster opening 5 and thence upwardly and outwardly to a point in line with the inner edge of the upper face of the journal box 26 and then outwardly substantially parallel with the upper surface thereof so as to form 50 a seat 27 therefor. The flanges 24 of the said member 22 are preferably inclined outwardly and upwardly, thereby forming a recess or channel 28 between the same and the inclined or wedge shaped side walls 11 55 of the bolster guide columns 7 and the inclined side walls 14 of the end portions of the member 2 are adapted to have a wedging engagement and to closely fit within the said channel 28. The shoulders 10, hereinbefore referred to, are adapted to engage the side 60 edges of the spring plank 29, and as will be noted from Fig. 1, the side edges of the said plank 29 also rest upon the inner ends of the extension 9 of the bolster guide columns.

65 The cooperation of the spring plank and the

bolster guide columns renders it unnecessary to employ rivets to connect the latter with the tension member 22. The pressure from the spring plank directed through the web shaped portions of the bolster guide columns 70 firmly wedges these guide columns within the channel 28 of the tension member. The engagement of the bolster guide columns through the shoulders 10 with the spring plank 29 prevents inward movement of the 75 guide columns, and the form or configuration of the lower tension member 22 on opposite sides of the bolster guide columns 27 prevents outward movement of the said columns due to pressure from the bolster. The 80 columns are thus effectually maintained in position without employing rivets or other suitable fastening means which heretofore have been employed at these points, and the omission of these rivets materially strengthens the side frame at these points by rendering it unnecessary to provide holes in the webs or flanges of the members at these points to receive the rivets.

The journal box seat portions 27 of the 85 member 22 are adapted to underlie the adjacent wall 15, and there is provided in each of said portions openings 30 which, when the members are in assembled position, register with the openings 16 in the wall 15.

To conveniently connect the lower journal box tie members (not here shown) to the tension member 22 the latter is provided with brackets 31, riveted or otherwise suitably connected to the web 23, said brackets 100 affording a simple, strong and reliable means for this purpose.

It will be observed that in this preferred form of side frame the top parts or compression member has a wedging engagement at 105 a plurality of spaced points with the lower tension member and that these members are not riveted or connected to each other except by this wedging engagement and by utilizing the journal box bolts, and it will 110 therefore be seen that in case of damage to the side frame either member may be removed and replaced without detriment to the other member and without requiring the cutting of rivets or the punching of rivet 115 receiving openings in the new members.

In the form of my device illustrated in Figs. 5 to 7, inclusive, the tension member 32 is substantially identical with the member 22 hereinbefore described, the only change 120 in the construction consisting in the extension of the lips 33 to the ends of the said member rather than terminating the said lips at an intermediate point as shown in Fig. 1. It is to be noted, however, that the 125 form of tension member 32 may be substituted for the tension member 22 should it be found desirable.

Since the general construction of the compression member 34 is also the same as the 130

member 2, it will only be necessary for a full understanding of this form to describe the points at which the modifications occur.

Adjacent the points of intersection of the 5 bolster guide columns 35 and the tension member 32 the said columns are provided with laterally extending flanges 36 and 37. The flanges 37 are shaped to conform to the adjacent portions of the lips 33 to which 10 they are connected by the rivets 38. At the lower ends of the flanges 36 there is provided a lateral extension 39 the inner ends of which are adapted to engage the spring plank 29. These extensions perform the 15 function of the shoulders 10 hereinbefore referred to. The connecting web which forms the inner face of the bolster guide columns is omitted from a point adjacent the upper ends of the flanges 36 and the side 20 walls 40 of each column below the flanges 37 are inwardly inclined so as to closely fit within the channel 28 of the tension member. At its outer ends the member 34 is 25 channel shaped in section instead of box shaped as shown in Figs. 1 and 2, and the side flanges 41 of the end portions adjacent their lower edges are provided with laterally extending lips 42 shaped to conform to the cutout portions of the lips 33 to which 30 they are connected by means of the rivets 43.

Having now fully described my invention, what I claim and desire to secure by Letters Patent, is:—

1. In a truck side frame, the combination 35 with a compression member comprising a cast beam furnished with integral bolster guides or strut columns, of a tension member comprising a channel shaped beam, portions of the said bolster guide columns being adapted 40 to have a wedging fit within the channel of the tension member, and means for connecting said members adjacent the ends thereof.

2. In a truck side frame, the combination 45 with a compression member of a flanged tension member adapted to cooperate therewith, the end portions of said members being adapted to contact, and means connecting said end portions, and bolster guide columns 50 integral with said compression member, said columns having the lower portions thereof spaced apart, the said portions of said bolster guide columns extending between and adapted to have a wedging engagement with 55 the flanges of the said tension member.

3. A truck side frame comprising a compression member provided intermediate the ends thereof with integral bolster guides, the

lower portions of which are spaced apart, and a tension member, the end portions of which 60 are connected to the corresponding portions of the compression member, said tension member having a wedge shaped recess therein adapted to receive portions of the said bolster guides, the side walls of said recesses 65 engaging the adjacent side walls of the bolster guides.

4. A truck side frame comprising a compression member provided intermediate the ends thereof with downwardly extending 70 bolster guide columns, a tension member having an upwardly facing channel, the ends of said columns having a wedging engagement with the side walls of the channel of the tension member.

5. A truck side frame comprising a compression member provided with spaced bolster guide columns, a tension member passing beneath and wedgingly connected to said columns, and means for connecting said compression member and said tension member, said means also being adapted to retain the journal boxes in assembled relation.

6. A truck side frame comprising a compression member furnished with imperforate integral guide columns, a tension member having a channel therein adapted to receive portions of said guide columns, and means on said columns for engaging a spring plank in line with the web thereof 90 to prevent the approach of the said columns.

7. A truck side frame comprising a compression member furnished with a plurality of wedge shaped portions, a tension member 95 cooperating with said compression member, said last named member having a wedge shaped channel therein, the said portions of the compression member being adapted to fit within the said channel of the tension member, and means for connecting said members adjacent some of the wedge shaped portions.

8. A truck side frame comprising a compression member, spaced bolster-guide columns connected thereto, a tension member having a channel therein adapted to receive portions of said guide columns, a spring plank adapted to extend between said guide columns, and means integral with said columns and extending under and engaging said spring plank whereby the said spring plank serves to maintain the guide columns in assembled position.

In testimony whereof I affix my signature.

CLARENCE H. WILLIAMSON.
